(57) **CLAIM**

The ornamental design for a display apparatus for eyewear, as shown and described.

DESCRIPTION

FIG. 1 is a perspective view of a display apparatus for eyewear showing my new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top view thereof;

FIG. 7 is a bottom view thereof;

FIG. 8 is a perspective view of a display apparatus for eyewear showing a second embodiment of the new design, secord embodiment being a mirror image of the first embodiment;

FIG. 9 is a front elevation view thereof;

FIG. 10 is a right side elevation view thereof;

FIG. 11 is a left side elevation view thereof;

FIG. 12 is a rear elevation view thereof;

FIG. 13 is a bottom view thereof; and,

FIG. 14 is a top view thereof.

The broken lines showing openings are for illustrative purposes only and form no part of the claimed design.
